SORTING MACHINE

Herman E. Veit, Parkville, Md., assignor to The
Glenn L. Martin Company, Baltimore, Md.

Application May 14, 1940, Serial No. 335,042

20 Claims. (Cl. 209—90)

The invention relates to machines and processes for sorting fasteners, and particularly to machines for sorting rivets or the like in accordance with the shape of their heads.

In modern factory practise, rivets are sent out from the stock room to various parts of the plant. Many of these rivets are dropped, and some are not used. All such dropped or unused rivets, of whatever size or type, are collected together and returned. This mixed mass of rivets must be separated, both as to length and as to type. This separation is a tedious and laborious process when carried out by hand.

The primary object of the present invention is to provide a machine which automatically separates different types of rivets.

The most common types of rivets are those having round and countersunk heads, and the object of the invention is to separate rivets in accordance with these two types of heads.

Another object of the invention is to provide a simple and effective machine for accomplishing this result.

Still another object is to provide auxiliary spring mechanism for tilting rivets of these two types in opposite directions so that they may be more easily assorted.

The invention includes a slot, preferably formed by two parallel endless bands, within which the stems of the rivets extend as they are fed to the separating mechanism. An additional object of the invention is to provide a novel arrangement for properly positioning the rivets in the slot.

Further objects and advantages of the invention will appear more fully from the following description, particularly when taken in conjunction with the accompanying drawings which form a part thereof.

In the drawings:

Fig. 1 shows in side elevation a machine embodying the invention;

Fig. 2 is a top plan view thereof;

Fig. 3 is a cross section on the line 3—3 of Fig. 2, with parts broken away;

Fig. 4 is a view from the left-hand end of Fig. 1;

Fig. 5 is a cross section on the line 5—5 of Fig. 2;

Figs. 6 and 7 are detail views of a portion of Fig. 3 showing the sorting means in operation on round head and countersunk rivets respectively; and

Fig. 8 is a perspective view of the agitating plate for the hopper.

The machine which embodies the invention disclosed herein includes a frame 2 adapted to rest on a suitable surface. At each end of the frame are shafts 4 and 6 on which are mounted wheels 8 and 10 respectively. Each of these wheels is in the nature of a pulley, and the wheels support two parallel endless belts 12 which are formed of steel or some other suitable material. The wheels are slightly spaced so that between the two belts 12 there is provided a slot 14. The width of this slot is equal to or perhaps slightly greater than the diameter of the stems of the rivets to be separated, but is less than the diameter of the heads of the rivets so that the rivets cannot fall through the slot if they are once arranged with their stems in the slot and their heads resting on the two belts.

The machine may be driven in any suitable manner, as for example by a crank 16 rigid on 20 the shaft 6.

The rivets to be separated are fed to the belts by a hopper 18. Means are provided for constantly agitating the rivets in the hopper and for preventing rivets from escaping from the hopper unless they are properly arranged between the two belts. Slidably mounted in the frame 2 by a slot 19 engaging bolts 21 is a bar 20 which at one end extends into the path of a series of pins 22 spaced around the outer face 25 of a wheel 23 mounted on shaft 4. The bar 20 is urged in the direction of the wheel by a tension spring 24 connected to the frame 2 and to a projection 26 of the bar, so that normally the bar 20 will be moved to the left in Fig. 3. Obviously pins 22, as the wheel 23 turns in the direction of the arrow, will strike the bar and push it to the right in Fig. 3, and will then pass below the bar whereupon the spring 24 will draw the bar to the left until it is engaged by the succeeding pin 22. The bar thus is given a reciprocating motion.

Secured on the bar and extending above and across one of the belts 12 is a member 28 which at the center of the machine has a plate-like 45 projection 30 extending into the bottom of the hopper 18. This projecting member is spaced above the belts 12 by approximately the thickness or longitudinal dimension of a rivet head as shown in Fig. 3, and thus it is impossible for a rivet to pass under the plate 30 unless its head is flat on the belts, and therefore unless its stem is arranged in the slot 14.

The left-hand end (Fig. 3) of plate 30 is provided with two upwardly directed portions 31 50 forming a transverse groove therebetween, this

notch engaging the lower edge of a plate 32 which extends from side to side of the hopper, and which is pivoted at 34 adjacent the top of the hopper on an upwardly extending frame portion 36. As the bar 20 moves back and forth, plate 30 reciprocates with it and oscillates plate 32, thus constantly agitating the rivets within the hopper 18. Thus the rivets are constantly turned upon themselves and some of them will fall into the proper position in slot 14 and will be fed out by the movement of the two belts in the direction of the arrow 38 beneath the plate 30.

As is stated above, the present invention particularly contemplates the separation of round and countersunk head rivets. For this purpose there is provided at the opposite ends of the belts, and adjacent the wheels 10, a pair of plates 40 having extensions 42 which are spaced apart by a space substantially equal to that of the slot 14, as represented by the slot 44. The left-hand or inner ends 46 of extensions 42 are located close to but slightly spaced from the belts 12 where they pass around wheels 10, the space being slightly less than the longitudinal dimension, or thickness, of the rivet head (indicated by t in Fig. 6). The plates 42 have some resiliency, so that the ends 46 may be moved in a slight arc by the rivets. The tips 46 are preferably not located directly above the axis of shaft 6, but somewhat to the outside thereof where the belts have started to curve as they pass around the wheels 10.

This mechanism alone, while not as desirable as the preferred form to be described below, is capable of separating round and countersunk rivets. As the rivets are moved along by the belts 12 with their heads resting on the belts and their stems extending into the slot 14, they reach the position shown in Figs. 6 and 7 respectively for the round and countersunk rivets. As will be seen from Fig. 6, the round head rivet will strike the tip 46 of member 42 at a point on the upper rounded surface of the rivet head. The inclination of this rounded surface will force the tip 46 upwardly, and the round head rivet will pass thereunder and will drop into a suitable container 48 placed at the bottom of the wheel 10. On the other hand, as shown in Fig. 7, when a countersunk rivet comes to the tip 46, the tip will strike on the under bevelled side of the rivet head and thus will lift the rivet from the belts 12 and onto the members 42. The rivet will then slide or be pushed by succeeding rivets down through the slot 44 and will drop into a suitable receptacle 50. The round and countersunk rivets will thus be separated.

With such a machine, however, there is some possibility that the round head rivets may tilt so far that their under edge will catch over tips 46, or that the bevelled head rivets will fail to tip and their top edge will catch under the tips 46. In order to make certain that proper separation occurs, the preferred form of the invention contemplates the provision of a single means which tilts round and countersunk rivets each in the proper direction to be separated by the tips 46.

Across the belts 12 just in front of the tips 46 (to the left in Fig. 3) there is provided a bar 52 having mounted on its lower side a bent piece 54 of resilient material such as spring steel. Normally the free portion of spring 54 above the belts 12 is spaced from the belts by a distance somewhat less than the longitudinal dimension

of the rivet heads. The effect of this spring is shown in Figs. 6 and 7. When spring 54 is used, ends 46 may be located adjacent belts 12 at a space substantially equal to the longitudinal thickness of the rivet heads so that the round head rivets may pass thereunder without contacting said ends.

As shown in Fig. 6, if a round head rivet is passed through the machine, when it meets the spring 54 it will be pushed inwardly by such spring until it is directed radially towards the shaft 6. The effect of this is to hold the head flat against the belts, or at a slight inclination to the horizontal, so that as the head moves to the position opposite tip 46 it is certain to pass under this tip and thus to the container 48.

On the other hand, when a countersunk rivet has passed until its center is slightly beyond the spring 54, the spring will exert a pressure on the rearwardly extending overhanging portion of the rivet head and will tilt it into the position shown in Fig. 7. In this position, the rivet is so far tilted that it must engage the tip 46 and thus be distributed to the container 50.

It seems obvious from the above that upon rotation of the handle 16 the rivets will be agitated in the hopper 18 and will be arranged in proper position between the belts 12. The belts will then carry the rivets to the separating mechanism which will distribute the round head rivets to one container and the countersunk rivets to the other.

While I have described herein one embodiment of my invention I wish it to be understood that I do not intend to limit myself thereby except within the scope of the appended claims.

I claim:

1. In a machine for separating round head and countersunk rivets, means forming a slot, means to feed rivets along said slot with their heads resting on said slot-forming means and their stems in the slot, and flexible means having a portion adjacent to said slot-forming means but spaced therefrom by a thickness not exceeding the longitudinal dimension of the rivet heads for removing the countersunk rivets from said slot-forming means, while permitting round head rivets to pass.

2. In a machine for separating round head and counter-sunk rivets, means including at least one belt forming a slot, means to feed rivets into said slot with their heads resting on said belt and their stems in the slot, means to drive said belt, and flexible means having a portion adjacent to said slot-forming means but spaced therefrom by a thickness not exceeding the longitudinal dimension of the rivet heads for removing the countersunk rivets from said slot-forming means, while permitting round head rivets to pass.

3. In a machine for separating round head and countersunk rivets, a pair of parallel belts forming a slot therebetween, means to move said belts so as to feed rivets along said slot with their heads resting on said belts and their stems in the slot, and flexible means having a portion adjacent to said belts but spaced therefrom by a thickness not exceeding the longitudinal dimension of the rivet heads for lifting the countersunk rivets from said belts.

4. In a machine for separating round head and countersunk rivets, a pair of parallel belts forming a slot therebetween, means to drive said belts, means connected to said belt-driving means to feed rivets into said slot with their heads resting

on said belts and their stems in the slot, and flexible means having a portion adjacent to said belts but spaced therefrom by a thickness not exceeding the longitudinal dimension of the rivet heads for lifting the countersunk rivets from said belts.

5. In a machine as claimed in claim 1, means adjacent said slot-forming means and in front of said flexible means for resiliently pressing on the heads of the rivets carried by said belts.

6. In a machine as claimed in claim 3, means adjacent said belts and in front of said flexible means for resiliently pressing on the heads of the rivets carried by said belts.

7. In a machine as claimed in claim 3, a spring mounted above said belts closely in front of said flexible means, said spring being normally closer to said belt than the longitudinal dimensions of the rivet heads, so as to bear on said rivet heads, to hold round head rivets with their stems normal to the belt surfaces and to tip countersunk head rivets with respect to the belt surfaces.

8. In a machine for separating round head and countersunk rivets, two pairs of pulleys, a pair of parallel belts mounted on said pulleys forming a slot therebetween, means to feed rivets along said slot with their heads resting on said belts and their stems in the slot, flexible means arranged adjacent to a portion of said belts passing around one pair of said pulleys, said flexible means having an end portion at a distance from the surfaces of said belts less than the longitudinal dimension of the rivet heads, and means to drive said pulleys whereby said end is engaged by the top surface of a round head rivet and pushed upwardly so that the rivet may pass therebeneath, whereas said end engages the undersurface of a countersunk rivet so as to transfer said rivet from said belts to said flexible means.

9. In a machine for separating round head and countersunk rivets, a path of parallel belts forming a slot therebetween, means to move said belts so as to feed rivets along said slot with their heads resting on said belts and their stems in the slot, tongues of flexible material having a slot therebetween of substantially the same width as said first slot, the ends of said tongues being arranged adjacent to said belts at a distance from the surfaces of said belts not exceeding the longitudinal dimension of the rivet heads, means to drive said belts in one direction, said ends pointing in the opposite direction to the direction of movement of said belts, whereby said round head rivets pass beneath said ends, whereas said ends engage the undersurface of a countersunk rivet so as to transfer said rivet from said belts into the slot between said members.

10. In a machine for separating round head and countersunk rivets, a path of parallel belts forming a slot therebetween, means to drive said belts, means connected to said belt-driving means to feed rivets into said slot with their heads resting on said belts and their stems in the slot, tongues of flexible material having a slot therebetween of substantially the same width as said first slot, the ends of said tongues being arranged adjacent to said belts at a distance from the surfaces of said belts not exceeding the longitudinal dimension of the rivet heads, means to drive said belts in one direction, said ends pointing in the opposite direction to the direction of movement of said belts, whereby said round head rivets pass beneath said ends, whereas said ends engage the undersurface of a countersunk rivet so as to transfer said rivet from said belts into the slot between said members.

11. In a machine as claimed in claim 9, means adjacent said belts and in front of said tongues for resiliently pressing on the heads of the rivets carried by said belts.

5. In a machine as claimed in claim 10, a spring mounted above said belts closely in front of said tongues, said spring being normally closer to said belt than the longitudinal dimensions of the rivet heads, so as to bear on said rivet heads, to hold round head rivets with their stems normal to the belt surfaces and to tip countersunk head rivets with respect to the belt surfaces.

10. In a machine as claimed in claim 3, said feeding means comprising a hopper having a portion above said belts and slot, a member slid able through one wall of the hopper in a direction parallel to the direction of movement of said belts, said member being spaced above said belts by a distance substantially equal to the longitudinal dimension of the rivet heads, and means to reciprocate said member.

15. In a machine as claimed in claim 10, said feeding means comprising a hopper having a portion above said belts and slot, a member slid able through one wall of the hopper in a direction parallel to the direction of movement of said belts, said member being spaced above said belts by a distance substantially equal to the longitudinal dimension of the rivet heads and means to reciprocate said member, said means being connected to said belt driving means and comprising a slid able member, spring means urging said member in one direction, and a wheel having pins thereon connected to said belt driving means and engageable with said member to push it in the opposite direction.

20. In a machine as claimed in claim 10, said feeding means comprising a hopper having a portion above said belts and slot, a member slid able through one wall of the hopper in a direction parallel to the direction of movement of said belts, said member being spaced above said belts by a distance substantially equal to the longitudinal dimension of the rivet heads, and means to reciprocate said member, said means being connected to said belt-driving means, a plate extending across said hopper, means mounting said plate for rocking movement at its top edge, and means connecting the bottom edge of said plate with said sliding member whereby reciprocation of said sliding member rocks said plate to agitate the rivets in said hopper.

25. In a machine having a pair of belts forming a slot therebetween and means to drive said belts, means for feeding fasteners into said slot comprising a hopper having a portion above said belts and slot, a member slid able through one wall of the hopper in a direction parallel to the direction of movement of said belts, said member being spaced above said belts by a distance substantially equal to the longitudinal dimension of the heads of the fasteners, and means to reciprocate said member.

30. In a machine having a pair of belts forming a slot therebetween and means to drive said belts, means for feeding rivets into said slot comprising a hopper having a portion above said belts and slot, a member slid able through one wall of the hopper in a direction parallel to the direction of movement of said belts, said member being spaced above said belts by a distance substantially equal to the longitudinal dimension of the rivet heads, and means to reciprocate said member, said means being connected to said belt-driving means and comprising a slid able member,

spring means urging said member in one direction, and a wheel having pins thereon connected to said belt-driving means and engageable with said member to push it in the opposite direction.

18. In a machine having a pair of belts forming a slot therebetween and means to drive said belts, means for feeding rivets into said slot comprising a hopper having a portion above said belts and slot, a member slideable through one wall of the hopper in a direction parallel to the direction of movement of said belts, said member being spaced above said belts by a distance substantially equal to the longitudinal dimension of the rivet heads, and means to reciprocate said member, said means being connected to said belt-driving means, a plate extending across said hopper, means mounting said plate for rocking movement at its top edge, and means connecting the bottom edge of said plate with said sliding member whereby reciprocation of said sliding member rocks said plate to agitate the rivets in said hopper.

19. In a machine for separating round head and countersunk rivets, two pairs of pulleys, a pair of parallel belts mounted on said pulleys forming a slot therebetween, means to feed rivets along said slot with their heads resting on said belts and their stems in the slot, and means adjacent to a portion of said belts passing around one pair of said pulleys to engage the heads of rivets and remove countersunk rivets only from said slot.

20. In a machine for sorting round head and countersunk head rivets, means forming a slot, means for feeding said rivets along said slot with their stems extending into the slot, means adjacent a portion of the slot, including means for tilting the countersunk rivets, and means for engaging the tilted heads of said countersunk rivets for removing the same from the slot, while permitting the round head rivets to pass.

20
